(57) CLAIM

The ornamental design for a hanging storage container, as shown and described.

DESCRIPTION

FIG. 1 is a perspective view showing an exemplary embodiment of our new hanging storage container design;

FIG. 2 is a front view thereof;

FIG. 3 is a rear view thereof;

FIG. 4 is a side view thereof;

FIG. 5 is a top view thereof;

FIG. 6 is a bottom view thereof; and,

FIG. 7 is a perspective view of the hanging storage container shown in a state of use with a horizontal rod and an additional hanging storage container as environment.

The broken lines illustrate portions of the hanging storage container and form no part of the claimed design. Additionally, the appearance of any portion of the claimed design between the jagged symbolic break lines forms no part of the claimed design.
